ROBERT K. JACK, OF NUTLEY, NEW JERSEY.

DUPLEX CENTRIFUGAL PUMP.

1,229,274.

Specification of Letters Patent. Patented June 12, 1917.

Application filed August 8, 1916. Serial No. 113,688.

To all whom it may concern:

Be it known that I, ROBERT K. JACK, a subject of the King of Great Britain, residing at Nutley, in the county of Essex and 5 State of New Jersey, have invented certain new and useful Improvements in Duplex Centrifugal Pumps; and I do hereby declare the following to be a full, clear, and exact description of the invention, such as will enable others skilled in the art to which it 10 pertains to make and use the same, reference being had to the accompanying drawings, and to characters of reference marked thereon, which form a part of this specification. 15 The present invention relates, generally, to improvements in fluid pumps; and the invention has reference, more particularly, to a novel construction of centrifugal pump. The present invention has for its 20 principal object to provide a very simple, compact and efficient construction of duplex centrifugal pump which will provide for the discharge of two streams under the impelling force of a rotary impeller. 25 A further object of the present invention is to provide a novel construction and arrangement of duplex centrifugal pump which is particularly adapted for use in maintaining circulation in the cooling systems of the modern V-shaped multi-cylinder gas-engine, now employed so extensively as the power plant of autovehicles, aeroplanes, etc. In such V-shaped multi-cylinder gas-engines, the cylinders are angularly disposed in two sets upon opposite sides of the 30 crank-shaft thereof; consequently it is found to be the better and more efficient practice to divide the circulation of the cooling medium serving such cylinders, which is obtained 35 from a suitable radiator reservoir, into two separately circulating streams, one for each set of cylinders. My present invention, therefore, provides a very simple and compact construction of duplex centrifugal 40 pump, which, through the rotation of a single driving-shaft and the impeller affixed thereon, is adapted to control and force the circulation of two separate and distinct streams of cooling medium, with a minimum 45 expenditure of power. Said novel duplex centrifugal pump will furthermore provide a proper equal flow efficiency to each stream, so that each set of engine cylinders receives its proper and necessary share of cooling 50 medium from the radiator constituting the source thereof.

A still further object of the present invention is to provide a duplex centrifugal pump so constructed and arranged that the impeller is subjected both to an axial balanced pressure and a balanced pressure at right angles to its axis during operation, consequently reducing side thrust, and the friction induced thereby, so that economy of driving power, and a more efficient utilization of said driving power is obtained. 60

Other objects of the present invention, not at this time more particularly enumerated, will be clearly understood from the following detailed description of the same. 70

With the various objects of the present invention in view, the same consists, primarily, in the novel construction of duplex centrifugal pump hereinafter set forth; and the invention consists, furthermore, in the 75 novel arrangements and combinations of the various devices and parts, as well as in the details of the construction of the said parts, all of which will be more fully described in the following specification, and then finally 80 embodied in the claims which are appended to and which form an essential part of the said specification.

The invention is clearly illustrated in the accompanying drawings, in which:— 85

Figure 1 is a side elevation or face view of the novel construction of duplex centrifugal pump, made according to and embodying the principles of my present invention.

Fig. 2 is a top edge or plan view of the 90 same.

Fig. 3 is a horizontal section of the same, taken on line 3—3 in said Fig. 1, looking downward.

Fig. 4 is a vertical cross section of the 95 same on line 4—4 in said Fig. 3, looking in the direction of the arrow x.

Fig. 5 is a side elevation of the novel construction of impeller, forming a part of my duplex centrifugal pump, the same being 100 removed from the latter; and Fig. 6 is an edge view or elevation of the same.

Similar characters of reference are employed in all of the hereinabove described views, to indicate corresponding parts. 105

Referring now to the said drawings, the reference character 1 indicates a complete duplex centrifugal pump, made according to and embodying the principles of my present invention, the same comprising a main body or casing 2, provided with any suitable design and arrangement of supporting 110

base or bracket 3. Said main body or casing 2 provides a centrally disposed chamber 4, in which the movable element of the pump, comprising a rotary impeller 5, is mounted. Located so as to extend around said chamber 4 are a pair of annular chambers *a* and *b*, which are divided or separated, one from the other, by a centrally disposed annular partition or wall 6. Said chambers *a* and *b* communicate with the impeller 5 by means of annular openings or passages 7 which extend around the periphery of said impeller 5. The annular chamber *a* is spirally enlarged from its point of beginning until it terminates in a discharge pipe 8, which extends toward the left hand at the upper side of the casing 2, and the annular chamber *b* is spirally enlarged from the point of its beginning until it terminates in a discharge pipe 9, which extends toward the right hand, at the lower side of the casing 2. As thus disposed and arranged it will be noted that both annular chambers *a* and *b* extend spirally in the same annular direction, but that the point of beginning of the one is diametrically opposite the point of beginning of the other, and that the discharge point of the one is diametrically opposite the discharge point of the other. The centrally disposed chamber 4 is preferably closed on one side by a side-wall 10, from which said base or bracket 3 preferably extends, while the opposite side of said chamber 4 is provided with an internally screw threaded opening 11, in which is screwed an externally threaded cover-plate 12, which thus serves to normally close said chamber 4, but also permits, when removed, access to said chamber 4 for the insertion therein, or removal therefrom, of said impeller 5.

Formed in said side-wall 10 is a centrally disposed opening or intake port 13, communicating with one side of said chamber 4. Formed preferably as an integral part of said side-wall 10, so as to terminate at and communicate with said opening or intake port 13, is an intake or suction pipe 14, extending transversely and outwardly therefrom. In like manner, formed in said cover-plate 12 is a centrally disposed opening or intake port 15, communicating with the opposite side of said chamber 4. Formed preferably as an integral part of said cover-plate 12, so as to terminate at and communicate with said opening or intake port 15, is an intake or suction pipe 16, extending transversely outwardly therefrom.

Integrally formed in the outer wall of said intake or suction pipe 14 is a gland 17, the outer end of which is threaded to receive a stuffing-box 18. Mounted in said gland 17 is a bearing bushing or seat 19. In like manner, there is integrally formed in the outer wall of said intake or suction pipe 16 a socket or thrust bearing-member 20,

within which is mounted a bearing bushing or seat 21. Journaled in said respective bearing bushings or seats 19 and 21 is a driving shaft 22. A suitable packing 23 is retained about said shaft where the same enters the bushing or seat 19 by the stuffing-box 18, thus preventing leakage through the shaft-bearing. Said impeller 5 is fixed upon and driven by said shaft 22. Of course it will be understood that, if it is desired to extend said driving shaft 22 through said cover-plate 12, a gland and stuffing-box may be substituted for said socket or thrust bearing-member 20.

Formed on the inner side of said side-wall 10 are a pair of concentrically disposed ground or machined bearing surfaces or seats 24; and in like manner, formed on the inner side of said cover-plate 12 are a pair of similar concentrically disposed ground or machined bearing surfaces or seats 25.

The impeller 5 is provided with a centrally disposed portion or wall 26 spaced between its opposite outer side walls 27, so as to provide two sets of impeller passages *a'* and *b'*. The impeller passages *a'* communicate, at their discharge ends located at the periphery of the impeller, with the annular opening or passage 7 leading into said annular chamber *a*; and the impeller passages *b'* communicate, at their discharge ends, with the annular opening or passage 7 leading into said annular chamber *b*. Each side wall 27 of said impeller 5 is provided with a centrally disposed receiving or entrance port 28, which respectively communicate with said intake port 13 on the one side of said chamber 4 and the intake port 15 on the other side of said chamber 4. The impeller passages *a'* and *b'* are formed by a series of 105 radially disposed curved impeller vanes or blades 29. Formed on the exterior side of the outer walls 27 of said impeller are concentrically disposed ground or machined bearing surfaces 30, which respectively ride 110 against the bearing surfaces or seats 24 and 25 respectively of the side wall 10 and cover-plate 12, so that the friction of the rotating impeller is reduced to a minimum.

In operation the impeller 5 is rapidly rotated within the chamber 4 by its driving shaft 22. The fluid to be pumped is delivered through the intake pipes so as to be received into the impeller through its centrally disposed entrance ports 28 on each side thereof. It therefore follows that the pressure of each stream, thus entering the impeller upon opposite sides thereof, is balanced one by the other since the pressure of the flow of one, tending to move the impeller axially in one direction, is counteracted by the pressure of the oppositely directed flow of the other, tending to move the impeller axially in an opposite direction; consequently the impeller when rotated is sub- 125 130 135 140 145 150 155 160 165 170 175 180

jected to an axial balanced pressure greatly reducing side thrust or play and consequent increased friction by reason of such thrust against the bearing surfaces or seats 24 and 25. Each stream of fluid thus entering the interior of the impeller is maintained separate from the other by said middle partition or wall 26. Consequently the two streams of fluid entering the impeller are 10 separately set in motion by the impeller vanes or blades 29 which contacting therewith set up the whirling or centrifugal action tending to forcefully eject the same therefrom and through the annular passages 15 7 respectively into the annular chambers *a* and *b*, the whirling force carrying the streams of fluid through said annular chambers *a* and *b* so that the same are forcibly discharged through the respective discharge 20 pipes 8 and 9 with considerable velocity. It will be understood that since the passages *a* and *b* are spirally enlarged from their points of beginning toward their discharge points at the discharge pipes 8 and 9, the 25 cross sectional areas thereof are constantly increasing toward such discharge points, and therefore the flow of the fluid displaced or discharged about the entire periphery of the impeller is not choked or checked since 30 the capacity of each chamber *a* and *b* is proportionally increased with the volume of discharge toward the exit through the discharge pipes 8 and 9. An additional novel feature in the construction and relation of 35 the chambers *a* and *b*, is found in their respective disposition or position relative to one another, whereby the points of their beginning and discharge are diametrically opposite each other. Such disposition thereof 40 tends to balance the pressure or reaction at the periphery of the impeller, and in lines at right angles to the axis thereof, since any pressure or reaction due to the discharge of the fluid at any particular point of the impeller is balanced by exactly the same pressure or reaction diametrically opposite, since 45 the combined cross sectional area of the chambers *a* and *b* at one point of discharge from the impeller is exactly the same as the combined cross sectional area of the said 50 chambers *a* and *b* at a point of discharge from the impeller diametrically opposite thereto. By thus constructing the pump so as to eliminate unbalanced pressure upon its 55 impeller either in the direction of its axis or at right angles thereto, it will be clearly evident that a very smooth and easy operation of the impeller is attained with a minimum degree of friction, and with a consequent 60 economical conservation of driving power in proportion to the work accomplished by the pump.

A still further novel feature of construction embodied in my novel pump, which 65 makes for beneficial results in the operation

thereof, comprises the construction of the impeller 5 wherein the outside walls 27 are provided. These walls, in conjunction with the central wall 26 provide inclosures over the impeller vanes or blades 28 whereby the 70 impeller passages *a'* and *b'* are provided, thus providing an unobstructed free passage, moving with the stream of fluid impelled thereby, so that the mass of fluid does not have to be moved against a stationary 75 surface with consequent friction, and tendency to cause impeding eddies therein which interfere with the free centrifugal movement of the fluid. By reason of this novel construction the efficiency of the pump 80 is increased, and a more efficient consumption of the power applied thereto for the operation thereof is attained.

I am aware that some changes may be made in the several arrangements and combinations of the various devices and parts of my present invention, as well as in the details of the construction of the same, without departing from the scope of the said invention as set forth in the foregoing specification, and as defined in the claims appended thereto. Hence, I do not limit my invention to the exact arrangements and combinations of the various parts as described in the foregoing specification, nor do I confine 95 myself to the exact details of the construction of the said parts as illustrated in the accompanying drawings.

I claim:—

1. In a device of the kind described, a 100 casing provided with a pair of annular chambers spirally enlarged from their points of beginning toward their points of discharge, annular passages formed at the juncture of said annular chambers with the 105 main body of said casing, the point of beginning and point of discharge of one of said annular chambers being respectively diametrically opposite the point of beginning and point of discharge of the other 110 annular chamber, a rotary impeller mounted within said casing adapted to discharge fluid through said annular passages into said respective annular chambers to forcibly eject said fluid from the latter at their 115 discharge points, and means for delivering fluid to said impeller.

2. In a device of the kind described, a 120 casing provided with a pair of annular chambers spirally enlarged from their points of beginning toward their points of discharge, annular passages formed at the juncture of said annular chambers with the main body of said casing, the point of beginning and point of discharge of one of 125 said annular chambers being respectively diametrically opposite the point of beginning and point of discharge of the other annular chamber, said casing being provided in its sides with intake ports, intake 130

or suction pipes connected with said casing so as to communicate with said intake ports, and a rotary impeller having radially disposed curved impeller vanes mounted 5 within said casing in communication with said intake ports, said impeller being adapted to discharge the fluid received through said intake ports peripherally through said annular passages into said respective annular chambers to forcibly eject said fluid from the latter at their discharge points.

3. In a device of the kind described, a casing provided with a pair of annular chambers spirally enlarged from their 10 points of beginning toward their points of discharge, annular passages formed at the juncture of said annular chambers with the main body of said casing, the point of beginning and point of discharge of one of 15 said annular chambers being respectively diametrically opposite the point of beginning and point of discharge of the other annular chamber, said casing being provided in its sides with intake ports, intake 20 or suction pipes connected with said casing so as to communicate with said intake ports, a rotary impeller having side walls, a central wall dividing the interior of said impeller transversely of its axis to form 25 two interior chambers open at the periphery of said impeller respectively to communicate with said respective annular passages leading to said annular chambers of said casing, radially disposed curved impeller 30 vanes extending through each interior chamber of said impeller, and the side walls of said impeller having centrally disposed entrance ports communicating respectively 35 with said intake ports of said casing.

4. In a device of the kind described, a casing providing a centrally disposed chamber, a fixed wall of said casing inclosing one side of said central chamber, a removable cover-portion closing the other 40 side of said central chamber, said casing being provided with a pair of annular chambers spirally enlarged from their points of beginning toward their points of discharge, discharge pipes connected with 45 said casing and extending outwardly from the respective points of discharge of said annular chambers, said casing being further provided with a pair of annular passages affording communication between said 50 central chamber and said respective annular chambers, the point of beginning and point of discharge of one annular chamber being respectively diametrically opposite the point of beginning and point of discharge of the 55 other annular chamber, a rotary impeller mounted within said central chamber of said casing adapted to discharge fluid through said annular passages into said respective annular chambers to forcibly eject 60 said fluid through said discharge pipes, a 65

driving shaft for operating said impeller, means connected with said casing and its cover-portion for journaling said shaft, and means for delivering fluid to said impeller.

5. In a device of the kind described, a 70 casing providing a centrally disposed chamber, a fixed wall of said casing inclosing one side of said central chamber, a removable cover-portion closing the other side of said central chamber, said casing being provided with a pair of annular chambers spirally enlarged from their points of beginning toward their points of discharge, discharge pipes connected with said casing and extending outwardly from the respective points of discharge of said annular chambers, said casing being further provided with a pair of annular passages affording communication between said central chamber and said respective annular chambers, the point of 75 beginning and point of discharge of one annular chamber being respectively diametrically opposite the point of beginning and point of discharge of the other annular chamber, said casing being provided respectively in its side wall and cover-portion with centrally disposed intake ports, intake or suction pipes connected respectively with said casing and its cover-portion so as to communicate with said intake ports, a rotary 80 impeller mounted within said central chamber of said casing, the same having radially disposed curved impeller vanes, said impeller being adapted to discharge the fluid received through said intake ports peripherally through said annular passages into said respective annular chambers to forcibly eject a stream of such fluid through the respective discharge pipe of each annular chamber, a driving shaft for said impeller, 85 and means connected with said casing and its cover-portion for journaling said shaft. 90

6. In a device of the kind described, a casing providing a centrally disposed chamber, a fixed wall of said casing inclosing one side 95 of said central chamber, a removable cover-portion closing the other side of said central chamber, said casing being provided with a pair of annular chambers spirally enlarged from their points of beginning toward their 100 points of discharge, discharge pipes connected with said casing and extending outwardly from the respective points of discharge of said annular chambers, said casing being further provided with a pair of annular 105 passages affording communication between said central chamber and said respective annular chambers, the point of beginning and point of discharge of one annular chamber being respectively diametrically opposite the point of beginning and point of discharge of the other annular chamber, said casing being further provided with a pair of annular 110 passages affording communication between said central chamber and said respective annular chambers, the point of beginning and point of discharge of one annular chamber being respectively diametrically opposite the point of beginning and point of discharge of the other annular chamber, said casing being further provided with a pair of annular 115 passages affording communication between said central chamber and said respective annular chambers, the point of beginning and point of discharge of one annular chamber being respectively diametrically opposite the point of beginning and point of discharge of the other annular chamber, said casing being further provided with a pair of annular 120 passages affording communication between said central chamber and said respective annular chambers, the point of beginning and point of discharge of one annular chamber being respectively diametrically opposite the point of beginning and point of discharge of the other annular chamber, said casing being further provided with a pair of annular 125 passages affording communication between said central chamber and said respective annular chambers, the point of beginning and point of discharge of one annular chamber being respectively diametrically opposite the point of beginning and point of discharge of the other annular chamber, said casing being provided respectively in its side wall and cover-portion with centrally disposed intake ports, intake or suction pipes connected re- 130

spectively with said casing and its cover-
portion so as to communicate with said in-
take ports, a rotary impeller having side
walls, a central wall dividing the interior
5 of said impeller transversely of its axis to
form two interior chambers open at the pe-
riphery of said impeller respectively to com-
munication with said respective annular pas-
sages leading to said annular chambers of
10 said casing, radially disposed curved im-
peller vanes extending through each interior
chamber of said impeller, said side walls of
said impeller having centrally disposed en-

trance ports communicating respectively
with said intake ports, a driving shaft for
rotating said impeller, and means connected
with said casing and its cover-portion for
journaling said shaft. 15

In testimony, that I claim the invention
set forth above I have hereunto set my hand 20
this 3rd day of August, 1916.

ROBERT K. JACK.
